UNITED STATES PATENT OFFICE.

VICTOR M. WITMER, OF MILWAUKEE, WISCONSIN.

JOIST.

Application filed January 10, 1927. Serial No. 160,227.

This invention relates to improvements in joists, and more particularly to steel or metallic joists.

It is the primary object of the present invention to provide a steel joist including a web bar embraced at its upper portions between a pair of longitudinally extending angle bars presenting a flat upper surface for the flush reception of various material for floors and roofs of buildings, and also permitting the insertion of hangers, bolts and the like.

A further object of the invention is to provide a steel joist in which the web bar is welded to the upper and lower bars and forming a strong and efficient joist for building construction.

A further object of the invention is to provide a joist which is of very simple construction, is strong and durable, is inexpensive to manufacture, and is well adapted for the purpose described.

With the above and other objects in view, the invention consists of the improved joist and its parts and combinations as set forth in the claims, and all equivalents thereof.

In the accompanying drawing in which the same reference characters indicate the same parts in all of the views:

Fig. 1 is side view of the improved joist; Fig. 2 is a cross sectional view thereof taken on line 2—2 of Fig. 1;

Fig. 3 is a side view of a slightly modified form of the invention; and

Fig. 4 is a cross sectional view thereof taken on line 4—4 of Fig. 3.

Referring now more particularly to the drawing it will appear that the numeral 6 indicates the bottom bar of the joist and the same is comparatively flat and rectangular in cross-section, as shown in Fig. 2. The end portions of the bottom bar 6 are bent angularly upwardly, as at 7, and then outwardly parallel with the intermediate portion, as at 8.

Welded at its points of contact with the upper face of the bottom bar 6 and extending upwardly therefrom is a web bar 9 of angular formation. Said web bar is preferably, although not necessarily, square in cross-section, as shown in Fig. 2.

The apexes of the web bar 9 are secured between a pair of longitudinally extending top angle bars 10, as shown in Fig. 2, said portions of the web bar being welded to the inner faces of the top bars. The angle bars

are positioned as shown in Fig. 2 with the faces 11 thereof at the top and in a horizontal plane.

In use, the end portions of the joist are supported on beams 12 and due to the arrangement of the angle bars 10 with the portions 11 uppermost and horizontal, a flat top is provided especially suited for supporting nailing strips, metal fabric, and the like. Also between the apexes of the web bar there are spaces between the inner faces of the angle bars 10 through which hangers, bolts, or the like may be extended, as required for fastening various articles. It should be further observed that all portions of the joist are of steel construction.

In the modified form of the invention shown in Figs. 3 and 4 the angle bars 10 are reversed with respect to their arrangement in Figs. 1 and 2, the faces 11 being lowermost and horizontal. This arrangement adapts the angle members for the support of various forms of floor and roof materials and units.

From the foregoing description it will be seen that the improved steel joist is of very simple and novel construction, and is well adapted for the purposes set forth.

What I claim as my invention is:

1. A joist, comprising a flat bottom member, a pair of angular top members, and an elongated intermediate member secured at various intermediate portions to the upper surface of the bottom member and to the top members, the upper portion of the intermediate member being interposed between the top members.

2. A joist, comprising a flat elongated bottom member with angular end portions, a pair of separated right-angularly shaped top members, and an intermediate member secured to the upper face of the bottom member and also secured to the top members, the upper portions of the intermediate member being interposed between the top members.

3. A joist, comprising an elongated flat bottom member, a pair of angular top members and an elongated intermediate member secured at various intermediate portions to the upper surface of the bottom member and to the top members, the upper portion of the intermediate member being interposed between the top members and holding the same in spaced relation.

4. A joist, comprising an elongated flat

bottom member, a pair of elongated angular top members, and an angularly bent web bar connected at a plurality of points at its lower portions to the upper face of the bottom bar and at its upper portions to the top members and interposed between the latter.

5. A joist, comprising a flat elongated bottom plate member with angular end portions,

a pair of right angularly shaped elongated top members, and an angularly bent web bar 10 welded at its lower portions to the upper face of the bottom plate and welded at its upper portions to the inner faces of the top members and interposed between the latter.

In testimony whereof, I affix my signature.

VICTOR M. WITMER.
